COMBINED INSULATED ROBE AND MASK

Rose M. Bland, St. Louis, Mo.

Substituted for abandoned application Serial No.
14,742, April 7, 1951. This application July 28,
1952, Serial No. 20,790

Term of patent 7 years

(Cl. D3—3)

To all whom it may concern:

Be it known that I, Rose M. Bland, a citizen of the United States of America, residing in the city of St. Louis and State of Missouri, have invented a new, original, and ornamental Design for a Combined Insulated Robe and Mask, of which the following is a specification, reference being had to the accompanying drawing, forming part thereof.

In the drawing:

Fig. 1 is a frontal perspective view of a combined insulated robe and mask, showing my new design;

Fig. 2 is a rear perspective view thereof on a reduced scale.

Fig. 3 is a perspective view of a combined insulated robe and mask on a further reduced scale, showing the same in an opened position.

This application is a substitute for my prior application D. 14,742 filed on April 7, 1951, and which is now abandoned.

I claim:

The ornamental design for a combined insulated robe and mask, as shown and described.

ROSE M. BLAND.
